Primary Examiner — Garth Rademaker*Assistant Examiner* — Joseph Thomas Hays(74) *Attorney, Agent, or Firm* — LegalForce RAPC Worldwide(57) **CLAIM**

The ornamental design for a tire, as shown and described.

DESCRIPTION

FIG. 1 is a front left side perspective view for a tire, showing my new design, the opposite side perspective view being a mirror image;

FIG. 2 a front elevational view of FIG. 1 thereof, the rear elevational, top plan and bottom plan view being a mirror image; and,

FIG. 3 is a left side elevational view of FIG. 1 thereof, the right side elevational view being a mirror image.

1 Claim, 3 Drawing Sheets(56)
